EVENING MECHANISM FOR COTTON OPENERS, &c.

No. 399,077.

Patented Mar. 5, 1889.

UNITED STATES PATENT OFFICE.

JAMES C. POTTER, OF PAWTUCKET, RHODE ISLAND.

EVENING MECHANISM FOR COTTON-OPENERS, &c.

SPECIFICATION forming part of Letters Patent No. 399,077, dated March 5, 1889.

Application filed January 29, 1889. Serial No. 297,907. (No model.)

To all whom it may concern:

Be it known that I, JAMES C. POTTER, of Pawtucket, in the State of Rhode Island, have invented a new and useful Improvement in 5 Evening Mechanism for Cotton-Openers, &c., of which the following is a specification.

My invention is directed to that portion of the evening mechanism of machines for opening and preparing cotton, &c., which is usually known as the "scale-lever system," consisting of a series of levers connected on the one hand to the individual evener-plates and on the other hand to the instrumentalities whereby motion is imparted to the belt-ship- 15 per of the cone-drum belt.

In my application for Letters Patent filed in the United States Patent Office July 9, 1888, Serial No. 279,395, I have described and claimed a scale-lever system having the scale- 20 levers below suspended from those next above, the topmost scale-levers being suspended from the evener-arms and the lowermost or main scale-lever being connected to the belt-ship- per-actuating mechanism.

My present invention is analogous to that 25 embraced in my application aforesaid, in that the instrumentalities which do the work of the scale-levers are suspended in connected series; but it differs therefrom in that I do 30 away with scale-levers and employ in lieu thereof curved bearing-pieces, in combination with supporting-straps, each of which passes peripherally around the under face of its curved bearing-piece below, and has its two 35 ends connected each to the center of one of two contiguous bearing-pieces above.

The nature of my invention and the manner in which the same is or may be carried 40 into effect will be readily understood by reference to the accompanying drawings, in which—

Figure 1 is a view, in side elevation, of so much of a cotton-opener as is needed to illustrate my invention. In this figure the parts 45 are represented diagrammatically in great measure with a view to indicate the relation which my improvement bears to the other parts of the evener system, which parts are well known to those skilled in the art to which 50 my invention pertains and require no detailed illustration or description for the purposes of

the present case. Fig. 2 is a front elevation of that portion of the evener mechanism in which my invention is comprised. Fig. 3 is an edge view of one of the curved bearing-surfaces, together with the link for connecting thereto the appropriate end of the supporting-strap. Fig. 4 is a front elevation illustrative of a modification, which will be hereinafter more particularly referred to. Fig. 5 is a view of one of the forked ends of the cross-bar to be used in said modification.

My invention is applicable to various forms of cotton-openers and the like. The form of machine in connection with which I 60 have illustrated my invention is that which is shown in a general way in my application for Letters Patent, Serial No. 279,395, hereinbefore referred to.

A is the frame of the machine. B is a combined evener and feed-roll supported in fixed bearings. C is a feed-roll supported in yielding bearings and co-operating with roll B for feeding purposes. D is one of a number of evener-plates, each having an arm, D'. E is 70 the knife-edge bar on which the evener-plates are fulcrumed. These parts are arranged together substantially in the same way as described in my aforesaid application, Serial No. 279,395.

G is the shipper, which controls the belt H of the cone-drums I J, motion being transmitted to the shipper from a rock-shaft, d, on which is fixed a toothed sector that plays through a slot in the front wall of the cone-drum box and engages the rack-bar L, fixed to said shipper, all substantially as described in my application for Letters Patent Serial No. 297,561, filed January 28, 1889. This rock-shaft has on it a sector, c, which by a strap, 80 b, and link a is connected to the lowermost curved bearing-piece of the system in which my invention, as hereinbefore stated, is comprised. On the rock-shaft is fixed a weighted lever, e, by which said shaft is normally influenced to keep the system of curved bearing-pieces and supporting-straps taut and to hold the evener-plates with yielding pressure against roll B.

Having described the machine in a general 90 way sufficiently to enable my improvement to be understood, I now proceed to a more par-

ticular description of that portion of the mechanism in which my present invention is comprised, said portion being between the evener-arms on the one hand and the link and strap 5 *a b* on the other hand.

The number of evener-plates employed varies in different machines. Some have eight plates, others have sixteen. In the present machine there are supposed to be eight plates, 10 this number being quite sufficient for purposes of explanation. Each plate has its arm or extension *D'*. Consequently there are eight arms, or, rather, four pairs of arms *D'*. With this number of plates the arms *D'* are usually 15 set four inches apart. Each pair of arms is connected to a curved bearing-piece, *F'*, by a flexible or pliable strap or band, *s*, of steel or other suitable material, which passes under the curved bearing-piece and has its upper 20 ends connected the one to one arm and the other to the other arm of the pair. This connection conveniently can be made by furnishing the ends of the strap with eyes *t*, into which the ends of the evener-arms *D'* hook. 25 The curved bearing-piece is a peripherally-grooved wheel or pulley, as shown in full lines in the drawings, the groove serving to retain the strap or band *s* upon it, although, if desired, the upper part of this wheel, which 30 practically is not in use, can be cut away, as indicated by dotted lines *m* in Fig. 2, in order to reduce weight and expense. The strap thus forms a loop, in the bight of which the curved bearing-piece rests and is supported, the legs 35 of the loop extending up and being connected with the two evener-arms appropriate to them.

The diameter of the wheel or curved bearing-piece is equal to the distance separating the two evener-arms of its pair, which in this 40 instance is four inches. Thus the legs of the loop hang vertically all the time, and consequently bring no lateral strain upon other portions of the system.

There being four pairs of evener-arms, *D'*, 45 there are in the topmost row or series four curved bearing-pieces, *F*, and four straps, *s*. In the row or series next below there are two curved bearing-pieces (which I will distinguish by the reference-letter *F²*) and two supporting-straps, *s*. In this second row each strap supports one of the curved bearing-pieces, *F²*, and at its ends is connected to the centers or axes *x* of one of the two pairs of curved bearing-pieces next above. This connection can be made in any suitable or 55 convenient way. In the drawings I have represented each wheel, *F'*, as provided with a pendent yoke, *w*, hung on the axial pintle *x* of the wheel and having below a hook, *v*, to engage the appropriate eye *t* of strap *s*. As the distance between the centers *x* of the pair of curved bearing-pieces or wheels *F'* is eight 60 inches, the diameter of the wheels or curved bearing-pieces *F²* in the row next below should be eight inches. Next below the series or 65 row *F²*, and supported in a similar way, is the single wheel or curved bearing-piece *F³*, Fig.

2, which corresponds in position and function to what in a scale-lever system is termed the "main-scale" lever. This wheel or curved 70 bearing-piece *F³* is sixteen inches in diameter, that being the distance between the centers *x* of the pieces *F²*. From the pintle *x* of piece *F³* hangs the link *a*, which by strap *b* is connected to the sector *c* of rock-shaft *d*, as hereinbefore stated. Through the intermediary of this system motion is transmitted to the belt-shipper from the evener-plates as efficiently as it would be by the ordinary scale-lever system. 80

In case sixteen evener-plates should be used, then the evener-arms usually would be but two inches apart. In this event there would be four instead of three series of curved bearing-pieces—eight in the top row 85 each two inches in diameter, four in the second row each four inches in diameter, two in the third row each eight inches in diameter, and one lowermost or main bearing-piece sixteen inches in diameter. These dimensions 90 of course could be somewhat varied without departure from my invention; but the best results will be obtained by following the formula above given.

I prefer to finish off the system with a 95 single piece, *F³*, as represented in Fig. 2; but it would be feasible to dispense with this lowermost piece and to employ in lieu thereof a cross-bar, *y*, provided with forked and hooked ends *y'*, as seen in Figs. 4 and 5, these forked 100 ends straddling the two bearing-pieces *F²* and hooking over the axial pintles *x* of said pieces. On the center of the cross-bar is hung a link, *z*, supported by a bearing-screw, *z'*, which screws through the top of the link and has its 105 pointed or rounded end seated in a cup-like cavity in the top of the cross-bar, so that the link may hang straight at all times. The link is connected by strap *b* to the sector of the rock-shaft, as in the other example. The screw 110 can be used (like the similar screw heretofore employed in evener systems) to effect the initial adjustment of the belt upon the cone-drums. This, however, is a well-known expedient heretofore employed and forms no part 115 of my present improvement.

What I claim herein as new, and of my own invention, is as follows:

1. The combination, with the evener plates and arms, of the described system of curved bearing-pieces and supporting-straps, each strap passing peripherally below and around its appropriate bearing-piece, the topmost series of straps being suspended by their ends from the evener-arms, and the straps of the other series being suspended from the centers of the curved bearing-pieces next above, substantially as and for the purposes hereinbefore set forth.

2. The combination, with the evener plates 130 and arms, the cone-drums, cone-drum belt and shipper therefor, and shipper-actuating mechanism, of the described system of curved bearing-plates and supporting-straps therefor,

each strap passing peripherally below and around its appropriate bearing-piece, the top-most series of straps being suspended by their ends from the evener-arms, the straps of the 5 other series being suspended from the centers of the bearing-pieces next above, and the lowermost or main bearing-piece being connected to the shipper-actuating mechanism, substan-

tially as and for the purposes hereinbefore set forth.

In testimony whereof I have hereunto set my hand this 28th day of January, 1889.

JAMES C. POTTER.
